UNITED STATES PATENT OFFICE.

JUSTIN SIGRIST, OF BATTLECREEK, MICHIGAN, ASSIGNOR OF ONE-HALF TO
HIRAM W. WILLIAMS, OF BATTLECREEK, MICHIGAN.

END FOR VEHICLE-SHAFTS.

SPECIFICATION forming part of Letters Patent No. 731,627, dated June 23, 1903.

Application filed December 1, 1902. Serial No. 133,421. (No model.)

To all whom it may concern:

Be it known that I, JUSTIN SIGRIST, a citizen of the United States, residing at the city of Battlecreek, in the county of Calhoun and State of Michigan, have invented certain new and useful Improvements in Ends for Vehicle-Shafts, of which the following is a specification.

This invention relates to improvements in ends for vehicle-shafts. In use vehicle-shafts are frequently broken at the ends, and such breaks are very difficult to repair so that the required strength is secured without injury to the appearance of the shafts. In the construction of shafts it is customary to finish the ends with a covering of patent or polished leather.

It is the object of this invention to provide an improved end for vehicle-shafts, whereby a broken shaft may be repaired and the appearance of the ordinary shaft retained or the end of a new shaft finished.

A further object is to provide an improved end for shafts which is strong and durable and economical to construct and use.

Further objects will definitely appear in the detailed description to follow.

I accomplish the objects of my invention by the devices and means described in the following specification.

The invention is clearly defined and pointed out in the claims.

A structure embodying the features of my invention is fully illustrated in the accompanying drawings, forming a part of this specification, in which—

Figure 1 is a side elevation view of a shaft end embodying the features of my invention. Fig. 2 is an enlarged detail cross-sectional view taken on a line corresponding to line 2 2 of Fig. 1, showing details of construction. Fig. 3 is a detail longitudinal sectional view taken on line 3 3 of Fig. 2.

In the drawings the sectional views are taken looking in the direction of the little arrows at the ends of the section-lines, and similar letters of reference refer to similar parts throughout the several views.

Referring to the lettered parts of the drawings, A is a tube suitably tapered formed of a strip of sheet metal having its edges se-

cured together by a double seam C. This tube is reinforced by an inner tube B, formed of a strip of sheet metal, one edge of which is clamped into the seam C, by which the edges of the metal forming the sheet A are united. The other edge of the strip of sheet metal forming the inner tube B is left free and terminates, preferably, at the edge of the seam C. The seam is prevented from opening, and the tubes are retained in proper relation to each other by an indentation C' in the metal at the edge of the seam, so that it is impossible to disengage the meeting edges of the metal forming the outer tube A, and the edge of the reinforcing-tube is prevented from withdrawing.

The inner tube B is slightly shorter than the outer tube A, and the end of the outer tube is folded inwardly and clamped upon the same at D, which securely clamps the inner tube in position and gives the structure a finished appearance, effectively removing any rough edges.

The inner tube preferably extends the entire length of the outer tube, though very satisfactory results are procured if it is extended only a portion of the way. The outer end of the tube is provided with a plug of wood adapted to fit the same snugly, and its inner end is adapted to fit over the end of the shaft and be secured thereto by rivets or the like, suitable perforations, as a, being provided to receive the same. The usual shaft-tip A' is provided for the outer end. By this arrangement of the parts they are securely and firmly united, and it is practically impossible to open the seam by crushing or the like in transportation or handling. The liability of injuring the structure in its application to the shaft is also reduced to a minimum, the parts being so firmly secured together. The structure is very strong and has a neat and finished appearance. While it is designed particularly for repair purposes, it is economical for use in new structures, as, owing to the superior finish possible by this construction, it very closely imitates the desirable leather finish.

I have illustrated and described my improved end for shafts in the form preferred by me on account of its strength and economy

in manufacture. I am aware that it is capable of considerable structural variation without departing from my invention.

Having thus described my invention, what I claim as new, and desire to secure by Letters Patent, is—

1. In a shaft end for vehicles, the combination of an outer tube A consisting of a strip of sheet metal with its edges secured together by a double seam C; an inner tube B fitting snugly within the outer tube, the said inner tube consisting of a strip of sheet metal, one edge of which is clamped by said seam C, the inner end of said outer tube being folded inwardly and clamped upon the said inner tube; an indentation C' in said tubes through the inturned part and at the side of said seam, whereby said parts are retained in position; and a suitable filling-plug in the outer end of said tubes, substantially as described.

2. In a shaft end for vehicles, the combination of an outer tube A consisting of a strip of sheet metal with its edges secured together by a double seam C; an inner tube B fitting snugly within the outer tube, the said inner tube consisting of a strip of sheet metal, one edge of which is clamped by said seam C; an indentation C' in said tubes at the side of said seam, whereby said parts are retained in position; and a suitable filling-plug in the outer end of said tubes, substantially as described.

3. In a shaft end for vehicles, the combination of an outer tube A consisting of a strip of sheet metal with its edges secured together by a double seam C; an inner tube B fitting

snugly within the outer tube, the said inner tube consisting of a strip of sheet metal; an indentation C' in said tubes at the side of said seam, whereby said parts are retained in position; and a suitable filling-plug in the outer end of said tubes, substantially as described.

4. In a shaft end for vehicles, the combination of an outer tube A consisting of a strip of sheet metal with its edges secured together by a double seam C; an inner tube B fitting snugly within the outer tube, the said inner tube consisting of a strip of sheet metal, one edge of which is clamped by said seam C, the inner end of said outer tube being folded inwardly and clamped upon said inner tube; whereby said parts are retained in position; and a suitable filling-plug in the outer end of said tubes, substantially as described.

5. In a shaft end for vehicles, the combination of an outer tube A consisting of a strip of sheet metal with its edges secured together by a double seam C; an inner tube B fitting snugly within the outer tube, the said inner tube consisting of a strip of sheet metal, the inner end of said outer tube being folded inwardly and clamped upon said inner tube, whereby said parts are retained in position; and a suitable filling-plug in the outer end of said tubes, substantially as described.

In witness whereof I have hereunto set my hand and seal in the presence of two witnesses.

JUSTIN SIGRIST. [L. S.]
